UNITED STATES PATENT OFFICE

ARTHUR J. BRAUER AND FREDERICK P. WAGNER, OF ST. LOUIS, MISSOURI

PROCESS AND APPARATUS FOR FORMING THE HEEL END OF A SOLE

Application filed February 10, 1930. Serial No. 427,279.

This invention relates to the art of making shoes, and more particularly to method and means for preparing the heel seat of the shoe. This application is a further embodiment of the method and apparatus of our Patent No. 1,852,288, granted April 5, 1932. In accordance with the particular embodiment described and shown in that patent, the heel end of the sole, while supported at the 10 margin adjacent the breast line, is supported only for a limited extent in lines extending back from the breast line and the cuts are correspondingly limited. This may necessitate the preliminary preparation of the sole 15 end.

One of the objects of this invention is to provide method and means whereby the sole may be formed without preliminary trimming.

20 Another object is to trim the sole not only at the sides but also at the back.

Further objects will appear from the detail description taken in connection with the accompanying drawing in which:

25 Fig. 1 is a perspective view of mechanism adapted for performing the heel seat forming operation;

Fig. 2 is a plan view of Fig. 1;

Fig. 3 is a view of the shoe bottom showing the heel seat formed; and

30 Fig. 4 is a perspective view showing the heel in place.

Generally stated and in accordance with this embodiment, the sole is concurrently supported on both sides of the shoe and at the sole margin not only adjacent the breast line but also back thereof to the end of the sole extension as formed and, in accordance with the embodiment illustrated, also at the back.

35 Cuts are taken through the sole margin normally against the supporting backing concurrently, not only at the ends of the breast line but also along lines extending back from the breast line to the end of the sole extension and, in the particular embodiment illustrated, also around the back.

40 Various mechanisms may be employed for performing the process, and this process may even be performed by elemental devices or 45 simple manipulations; the process is, how-

ever, best performed by suitable mechanism. In accordance with one embodiment of this invention, a backing die, preferably composed of a pair of relatively adjustable backing die elements, extends inwardly to support the sole peripherally on both sides adjacent the sole margin and the breast line and back to the end of the sole extension, and, in the particular embodiment described, also at the back. A cutter, which may also be composed of relatively adjustable cutting elements, is positioned to cut through the sole margin normally against and inside of the die; this die and cutter have co-operating cutting edges extending outwardly along the breast line and back from the breast line to the end of the sole extension, and, in the particular embodiment described, also around the back.

50 Referring now to Figures 3 and 4, which illustrate a shoe of the McKay type, 7 designates the upper of a shoe which is lasted over the heel seat, as shown at 10, and, where employed over an insole 9, the upper being secured by fasteners 11 in the usual manner. 55 An outsole 4 is secured by a line of stitches 12, which, in a McKay shoe, pass through the upper and insole.

50 In performing the process embodying this invention, the heel end of the sole need not be preliminarily trimmed but can be left wholly unformed; it may or may not be secured by a tack 14 at the heel seat. In performing the operation, the sole is supported adjacent and back of the breast line on both 60 sides and back to the end of the sole extension 61 to be formed, and, if desired, also along the back. Cuts are then taken along the breast line to form shoulders 30, and these cuts extend back to the end of the sole 65 extension 61, and, if desired and as herein-after described, these cuts may also extend around the end of the sole extension.

70 The sole extension may, therefore, be completely formed for the reception of the heel 75 21, which as illustrated is of the Louis type provided with a covering, a breast 20, and a top lift 22. This heel may be positioned against the shoulders 30 at the breast line 80 100

and, after being secured, the usual flap 62 may be pasted against the breast.

Figs. 1 and 2 show mechanism adapted for the formation of the extension or tongue portion 61 to the shoulders 30. It comprises a base 35 having posts 36 and 37, the latter being movable in guides 38 on the base so as to be shiftable or adjustable towards and from the former. A lever 39 pivoted at 40 on the guide 38 and having a slot 41 engaging a pin on 37, is arranged to provide for moving the post 37. Mounted on each of the posts 36 and 37 is a backing die element 43 adapted for engagement with co-operating cutter elements 44. Each of these cutters 44 is mounted on a head 45 held in a raised position by springs 46 and guided by pins 47, as well as additional pins (not shown) encircled by the springs 46. This base 35 may be placed on a suitable press provided with a movable ram (not shown but as shown in Patent No. 1,852,288) adapted to engage the heads 45 in order to cause the cutters 44 to engage the die elements 43. The ends of the cutters 43 are reduced in thickness and preferably beveled so as to readily take into the crease between the upper and the extensions of the sole where the sole is attached at the heel. In this embodiment, however, each of the die elements 43 has an inward extension 63, while each of the cutters 44 has an inward extension 64; moreover, each of the heads 45 has an extension 65 embracing the cutter part 64. It will be seen that the edges of the die and cutter elements extend to the end of the sole extension when trimmed. The function of the cutter parts 63 and 64 is to terminally reduce or cut off the end of the extension 61.

In the operation of the mechanism for performing the process, the heel is placed on the shoe and the breast line is marked thereon. The flap or part 62 when present is then turned back and the shoe placed between the die elements 43, with the breast line as marked on the sole part 61 coinciding with the forward edges of the elements and with these cutters pressed between the creases between the upper and the sole extensions if the latter is tacked to the upper. In this embodiment the cutter extensions 63 and 64 act as stops to space the inside edges of the cutters 43 to correspond to the heel. The heads 45 are then depressed, thereby operating to not only marginally reduce the sole extension 61 to correspond to the heel, but also to terminally reduce or cut off this extension to the required length so as to fit the heel.

It will be noted that in accordance with this invention the die cutting elements 43 and 44 are moved inwardly until they are arrested by their stops; accordingly the width of the extension is accurately predetermined to correspond to the heel while the length of the extension is also predetermined. On account

of the beveled or even sharpened nature of the edges of the die elements 43 and the leverage secured by the lever connection, these cutters can be forced into the creases between the sole and the upper to the required extent if the sole is tacked to the upper at the heel. The distance between the edges of the die elements 43 can be taken as a gauge of the width of the heel seat. It will, therefore, be seen that all hand fitting can be eliminated.

As previously noted and as shown in Figures 1 and 2, the movement of the post 37 towards the post 36 can be, and is, limited in the particular embodiment by the engagement of the die and cutter elements. These, when together, determine not only the width of the sole extension but also the length of that extension from the shoulders 30 to the end of the extension. With the parts in that position, the shoe with the sole thereon can be moved into engagement with the die elements 43 which extend inwardly, as well as the back portions 63 taking under the sole extension. That is particularly true where, as in some classes of work, it is neither necessary nor desired to tack down the end of the sole extension, but rather to leave the same free. With the sole thus supported from the breast line marginally to the end of the sole extension, and in the particular embodiment also around the back, the cutter elements will operate to completely form the sole extension. It will be noted that the cutter elements co-operate with the inside edges of the die elements so that a clean cut will be secured without requiring the cutter elements to take against a backing extending completely across the sole extension. In this way, the life of the cutter element edges is not only extended, but a cleaner cut will be secured.

While this invention is particularly applicable to shoes having the general types of heels shown and described, it will be understood that this invention is applicable in many cases to other forms and types of heels. It is further applicable to shoes having soles and bottoms of different types and attached by various means, whether by stitching, cement or even by metallic fasteners. It will furthermore be understood that certain features, operations and sub-combinations are of utility and may be employed without reference to other features, operations and sub-combinations; that is contemplated by and is within the scope of the appended claims. It is moreover obvious that various changes may be made in the details of operations and constructions within the scope of the appended claims, without departing from the spirit of this invention; it is to be understood, therefore, that this invention is not to be limited to the specific details shown and/or described.

Having thus described the invention, what is claimed is:

1. The process of forming a tongue por-

- tion in the heel end of a sole while on a shoe, comprising, supporting the sole concurrently on both sides of the shoe but only at the sole margin adjacent the breast line and back thereof to a point defining the end of the tongue portion to be formed, and cutting through the sole margin normally against the supporting backing concurrently at the ends of the breast line and along lines extending back from the breast line toward the end of the sole when so supported. 5
2. The process of forming a tongue portion in the heel end of a sole while on a shoe, comprising, supporting the sole concurrently on both sides and at the back of the shoe but only at the sole margin adjacent the breast line and back thereof to and around the end of the tongue portion to be formed, and cutting through the sole margin normally against the supporting backing concurrently at the ends of the breast line and along lines extending back from the breast line to and around the end of the tongue portion when the sole is so supported. 10
3. The process of forming a tongue portion in the heel end of a sole while on a shoe, comprising, supporting the sole concurrently on both sides of the shoe by a peripheral backing providing inside edges adjacent and along the sole margin and the breast line and back thereof to a point defining the end of the tongue portion to be formed, and cutting through the sole margin normally against the inside edges of the supporting backing at the ends of the breast line and along lines extending from the breast line toward the end of the sole when so supported. 15
4. The process of forming a tongue portion in the heel end of a sole while on a shoe, comprising, supporting the sole concurrently on both sides and at the back of the shoe by a peripheral backing providing inside edges adjacent and along the sole margin and the breast line and back thereof to and around the end of the tongue portion to be formed, and cutting through the sole margin normally against the inside edges of the supporting backing at the ends of the breast line and along lines extending from the breast line to and around the end of the tongue portion when the sole is so supported. 20
5. A machine for forming a tongue portion in the heel end of a sole while on a shoe, comprising, backing means extending inwardly to provide inside edges supporting the sole peripherally on both sides adjacent the sole margin and the breast line and back thereof to a point defining the end of the tongue portion to be formed, and means for cutting through the sole margin normally against the inside edges of the supporting backing at the ends of the breast line and along lines extending from the breast line toward the end of the sole when so supported. 25
6. A machine for forming a tongue portion in the heel end of a sole while on a shoe, comprising, a backing die extending inwardly to provide inside edges supporting the sole peripherally on both sides adjacent the sole margin and the breast line and back to a point defining the end of the tongue portion to be formed, and a cutter positioned to cut through the sole margin normally against and inside of the die, said die and cutter having co-operating cutting edges extending outwardly along the breast line and back from the breast line toward the end of the tongue portion when the sole is so supported. 30
7. A machine for forming a tongue portion in the heel end of a sole while on a shoe, comprising, a backing die extending inwardly to support the sole peripherally on both sides adjacent the sole margin and the breast line and back to a point defining the end of the tongue portion to be formed, and a cutter positioned to cut through the sole margin normally against and inside of the die, said die and cutter having co-operating cutting edges extending outwardly along the breast line and back from the breast line toward the end of the tongue portion when the sole is so supported. 35
8. A machine for forming a tongue portion in the heel end of a sole while on a shoe, comprising, a backing die extending inwardly to support the sole peripherally on both sides and at the back adjacent the sole margin and the breast line and back to and around the end of the tongue portion to be formed, and a cutter positioned to cut through the sole margin normally against and inside of the die, said die and cutter having co-operating cutting edges extending outwardly along the breast line and back from the breast line to and around the end of the tongue portion when the sole is so supported. 40
9. A machine for forming a tongue portion in the heel end of a sole while on a shoe, comprising, a pair of relatively adjustable backing die elements extending inwardly to support the sole peripherally on both sides adjacent the sole margin and the breast line and back to a point defining the end of the tongue portion to be formed, and a pair of relatively adjustable cutting elements co-operating with said die elements to cut through the sole margin normally and inside of the die elements, said die and cutting elements having co-operating edges extending outwardly along the breast line and back from the breast line toward the end of the sole when so supported. 45
10. A machine for forming a tongue portion in the heel end of a sole while on a shoe, comprising, a pair of relatively adjustable backing die elements, extending inwardly to support the sole peripherally on both sides and at the back adjacent the sole margin and the breast line, and a pair of relatively adjustable cutting elements co-operating with said die elements to cut through the sole mar- 50

gin normally and inside of the die elements,
said die and cutting elements having co-op-
erating edges extending outwardly along the
breast line and back from the breast line to
5 and around the end of the tongue portion to
be formed when the sole is so supported.

In testimony whereof we affix our signa-
tures this 8th day of February, 1930.

ARTHUR J. BRAUER.
10 FREDERICK P. WAGNER.
